CENTRIFUGAL CONTROL FOR TIMERS

James L. Arthur, Ind., assignor to
General Motors Corporation, Detroit, Mich., a
corporation of Delaware

Application October 7, 1935, Serial No. 43,892

13 Claims. (Cl. 200—31)

This invention relates to ignition timer distributors and has to do with improvements in means for controlling the centrifugal advance range for altering the time of ignition.

5 One of the objects of the invention is to combine a holddown plate with stop means for limiting the range of flyweight movement.

Another object of the invention is to provide 10 adjustable stop means whereby the range of flyweight movement may be altered.

A further object of the invention is to improve 15 centrifugal mechanism for altering the time relation of fuel ignition in response to engine speed.

15 Further objects and advantages of the present invention will be apparent from the following description, reference being had to the accompanying drawings wherein a preferred embodiment of one form of the present invention is clearly shown.

20 In the drawings:

Fig. 1 is a vertical section through a timer distributor illustrating the improvements herein disclosed.

25 Fig. 2 is a plan view of the holddown plate and stop means for the improved centrifugal mechanism.

Fig. 3 is a plan view of the centrifugal mechanism with the holddown plate and stop means 30 assembled in position.

35 Fig. 4 is a fragmentary view in section substantially as illustrated by the line and arrows 4—4 of Fig. 3.

Fig. 5 is an elevational view of the speed responsive mechanism.

40 Fig. 6 is a horizontal sectional view through the holddown plate substantially as indicated by the line and arrow 6—6 of Fig. 1 illustrating the flyweights in their in position.

Fig. 7 is a view similar to Fig. 6, but illustrating the flyweights moved to their outer position.

45 Fig. 8 is a view similar to Fig. 7, but illustrating the holddown plate and stop means moved to a second position whereby the range of flyweight movement is altered.

Fig. 9 is a modification of a holddown plate and stop means.

50 Referring particularly to the specification 10 indicates the usual distributor cup having a shank portion 12 drilled to provide a bearing for a driving shaft 14. The open end of the housing 10 is closed by a distributor cap 16 providing the terminals 18 and 20 cooperating with the conducting elements 22 and 24 respectively of a rotor 26, supported by a cam 28 variably

driven by the shaft 14 through the agency of a speed responsive mechanism 30 later to be described. Supported within the housing 10 is a breaker plate 32 having a flange 34 providing an inner race for a series of ball bearings 36 5 equally spaced about the plate by a spacing band 48 operating to maintain the balls 36 in operative engagement within an outer race 42, provided by the housing 10. The breaker plate 32 10 supports a contact bracket 44 to which is secured the usual fixed contact that cooperates with a movable contact carried by breaker lever 46, oscillatable about a pivot 48 through the agency of a rubbing block periodically engaged by the cam 28. The breaker lever 46 is urged into engagement with the cam 28 by means of a spring 50 that operates to electrically connect the movable contact with the addition of the lead 52, to a terminal post 54 insulatedly supported by the housing 10. Means are provided 15 for shifting the breaker plate 32 in response to engine developed suction by means of a displacement unit 56, provided with a link 58 pivoted to the breaker plate 32 by means of the device 60. Inasmuch as the breaker plate 32 20 with its ball bearing support, and the circuit breaker structure is fully disclosed and claimed in a copending application, further description is not deemed necessary herein.

The centrifugal mechanism 30, hereinbefore referred to, comprises a weight base 62 press fitted upon a knurled portion 64 of the driving shaft 14 at a point removed from its reduced end 66. Secured within the weight base 62 and at substantially diametric points, there are a pair 35 of pivot posts 68 upon each of which there is pivoted a flyweight 70 that has a cam engaging arm 72 as well as a weight arm 74. The cam engaging arm 72 is designed to have rolling engagement with the cam face 76 of a cam bar 78, which cam bar is press fitted or otherwise secured upon a reduced portion 80 of the cam 28 or an extension thereof, substantially as illustrated in Fig. 1. The cam 28 has a cylindrical bore 82 providing a bearing for the reduced end 40 portion 66 of the shaft 14. Thus it will be seen that the cam 28 is capable of limited rotation, or oscillating movement, upon the extension of the shaft 14 through the centrifugal mechanism. 45

In order to further control the amount of angular rotation of the cam 28 upon the shaft extension 66, the cam bar 78 is provided with a pair of spring posts 84 to which springs 86 are connected and thence hooked over the pivot post 68; the springs 86 operating to maintain the fly- 50 55

weights and cam bar in compact relation substantially as illustrated in Figs. 3 and 6, wherein the weight arms 74 are held in the inward position close to the extension 89 of the cam. 5 Spacers 88 are disposed about the pivot posts 68 and between the weight base 62 and the flyweights 70, and ribs 90 are provided on the weight base 62 for spacing the weights slightly above the weight base and for reducing the frictional 10 resistance of their inward and outward travel.

Means are provided for confining the weights in their lateral movement upon the pivot post, and for defining the extent of outward movement. These means include holddown plate 136, which holddown plate is in the form of a shallow cup having a bottom wall 102 with a depending flange or skirt 104. The bottom wall of the cup is provided with an elongated aperture 103 of sufficient dimension that the plate 15 may be passed down over the cam 28, and thence moved sideways so that the skirt 104 will substantially embrace the centrifugal mechanism. A second elongated aperture 108 is also provided, and, along with the aperture 103 provide means 20 such that the plate may be passed down over the end of the pivot posts 68, the spring posts 84 and the connecting springs 86, and yet allow for clearance of the spring post 24 when rotative movement occurs between the weight base 62 25 and the cam bar 78. Still other apertures as the arc like slots 110 are provided that pass over the reduced threaded end 112 of studs 114 secured at diametric points on the weight base 62, thus providing means for holding the holddown plate 30 103 in spaced relation to the weight base 62, that the flyweights may move radially without meeting with obstruction. At appropriate points about the skirts of the holddown plate, there are deformed portions 120 so positioned that when 35 the holddown plate is assembled with the weight base, the tip ends 122 of the flyweights will engage the deformed portions when the flyweights travel to their outer extreme, as illustrated in Fig. 7. The relation of the deformed portions 40 120, and the stud receiving slots 110, are such that rotation of the holddown plate with respect to the weight base will alter the point of engagement between the deformed portion 120 and the tip 122 of the flyweight. Also the relation of the 45 flats 123 is such that relative angular movement of the plates to one extreme permitted by the slots 110 and studs 114 there will be one point of engagement that will be nearer the axis of rotation than when the two plates are at the other 50 extreme of relative angular movement permitted by the slots and stud. Thus, the radial distance from the axis of the assembly to the point of engagement between the deformed portion and the tip of the flyweight is lengthened or shortened 55 depending on the position of the holddown plate and weight base. When the holddown plate and weight base have been moved to the desired relative position they may be secured in place by an appropriate nut 124 tightened on the 60 stud 114.

Fig. 8 is illustrative of the results that may be accomplished by relative rotation of the holddown plate and the weight base. Arrow A indicates that the holddown plate has been moved upon the weight base the limit provided by the slot 110 and stud 114, the parts taking the position illustrated in the full line position of the flyweights. When the holddown plate has been moved to the opposite extreme provided by the slot 110 and stud 114, all of which is indicated

by the arrow B, the relation of the parts will then take the position illustrated in the dotted line showing of the holddown plate and flyweights. While the construction thus far described embodies a deformed portion of the skirt 120 as comprising a flat, other forms of deformations may be utilized, and a modification of that is illustrated in Fig. 7. In that form, the bottom wall 202 of the holddown plate is apertured at 211 so as to leave a bendable portion 220 of the skirt 10 15 204 comprising the deformed portion, the remaining portions of the holddown plate being substantially identical with that hereinbefore described, all of which are indicated with the addition of 100 to the reference characters. 15

In this modified form, the limits of outward travel of the flyweights 70 are determined by bending the deformed portion 220 inward substantially as indicated, whereupon the flyweight 70 is engaged by the tip 122 as shown in full lines, 20 or the deformable portion 220 may be bent outwardly as indicated at 220a thus extending the range of outward movement as indicated by the dashed line position of the flyweight 70. 25

While the embodiment of the present invention as herein disclosed, constitutes a preferred form, it is to be understood that other forms might be adopted, all coming within the scope of the claims which follow. 25

What is claimed is as follows:

1. An ignition timer comprising in combination, a circuit breaker, a cam for operating a circuit breaker, a driving shaft, means drivingly connecting the shaft with the cam comprising, a weight base secured to the shaft, a cam bar 35 secured to the cam, a pair of studs provided by each of the bars and the weight base, flyweights pivotally mounted upon the studs of the weight base and having an arm engaging the cam bar, springs secured to a stud of each pair, and a 40 holddown plate superimposed over the cam bar and flyweights for guiding the outward movement of the flyweights, and means including a depending flange from the holddown plate limiting the outward movement of the flyweights. 45

2. An ignition timer comprising in combination, a circuit breaker, a cam for operating a circuit breaker, a driving shaft, speed responsive mechanism drivingly connecting the shaft and cam, said speed responsive mechanism comprising, a 50 weight base, flyweights pivotally secured to the weight base, a cam bar mounted on the circuit breaker cam, and normally urged to engage the flyweights, a holddown plate substantially enclosing the cam bar and flyweights, and means 55 provided by the holddown plate for limiting the outward movement of the flyweights.

3. An ignition timer comprising in combination, a circuit breaker, a cam for operating a circuit breaker, a driving shaft, speed responsive mechanism drivingly connecting the shaft and cam, said speed responsive mechanism comprising, a weight base, flyweights pivotally secured to the weight base, a cam bar mounted on the circuit breaker cam, and normally urged to engage the 60 flyweights, a shallow cup inverted over the flyweights and cam bar, means supporting the cup from the weight base in spaced relation with the said weights and bar, and means comprising a portion of the side wall of the cup for limiting 70 the outward movement of the flyweights.

4. An ignition timer comprising in combination, a circuit breaker, a cam for operating a circuit breaker, a driving shaft, speed responsive mechanism drivingly connecting the shaft and 75

cam, said speed responsive mechanism comprising, a weight base, flyweights pivotally secured to the weight base, a cam bar mounted on the circuit breaker cam, and normally urged to engage the flyweights, a plate member superimposed over but spaced from the cam bar and flyweights, and depending portions from the plate member disposed for engagement by the free ends of the flyweight thereby limiting the outward movement of the flyweights.

5. The combination set forth in claim 1 wherein the holdown plate is apertured so as to pass over the studs and springs and permit their lateral movement, said holdown plate having provisions 10 for limited rotation with respect to the weight base whereby the limits of outward flyweight movement may be altered.

6. In a timer having a circuit breaker and an engine operated cam for actuating the circuit breaker, the combination of means for altering the angular relation of the cam to the circuit breaker in response to engine speed comprising in combination, a driving shaft, a support provided by the shaft and rotating therewith, flyweights pivoted upon said support, a cam bar secured to the cam and spring urged to normally engage the flyweights, and holdown means for guiding and limiting the movement of the flyweights, said holdown means comprising, a plate

20 having apertures whereby the plate may be passed over the cam and the spring urging means maintaining the flyweights in centralized position, means for securing the plate to the support in spaced relation with the flyweights, said securing means including arcuate slots in the plate disposed over threaded studs on the support whereby the plate may be moved angularly relative to said support, and depending flat portions provided by the holdown means disposed at the outward 30 limit of flyweight travel whereby the flyweights are brought to rest at a predetermined point, the rotation of said plate relative to the support operating to change the radial distance at which the flyweights come to rest.

40 7. In a timer having a circuit breaker and an engine operated cam for actuating the circuit breaker, the combination of means for altering the angular relation of the cam to the circuit breaker in response to engine speed comprising in combination, a driving shaft, a support provided by the shaft and rotating therewith, flyweights pivoted upon said support, a cam bar secured to the cam and spring urged to normally engage the flyweights, and holdown means for guiding 50 and limiting the movement of the flyweights, said holdown means comprising, a sheet metal cup disposed over the flyweights and whose side walls depend over the support, said side walls providing flats disposed at the point of flyweight engagement for limiting the outward movement of the flyweight.

8. In an ignition timer, a speed responsive mechanism comprising in combination, a shaft, a weight base mounted intermediate the ends of said shaft and provided with a pair of pivot posts, a cam mounted for oscillatable movement upon one end of the shaft and providing a cam bar, spring posts mounted in each end of the cam bar, flyweights mounted on the pivot posts, and springs secured to the spring post and pivot post for maintaining the flyweights in compact relation, 10 a holdown plate apertured to fit over the cam, springs, and supporting post and be disposed in close relation to the flyweights and cam bar, means spacing the plate from the weight base and providing for limited rotation of the plate 15 with respect to the base, said plate having a depending skirt substantially enclosing the weight base, and deformed portions in the depending skirt for limiting the outward throw of the flyweights.

9. The combination set forth in claim 8 in which the deformed portions of the skirt comprise flats angularly shiftable by the limited rotation of the plate relative to the weight base for altering the range of outward travel of the flyweights.

10. The combination set forth in claim 8 in which the deformed portions of the skirt comprise, bendable sections for varying the limitation of flyweight travel.

11. The combination set forth in claim 8 in which the plate is apertured opposite the skirt deformations to weaken the skirt support, and wherein the skirt deformations may be bent toward or from the shaft for varying the extent of flyweight travel.

12. In a speed responsive mechanism for an ignition timer, wherein flyweights and a cooperative cam bar operate to effect an angular shift between a pair of coaxial shafts in response to variation in driven speed of one of the shafts, 40 holdown means and weight stops for the flyweights, comprising in combination, a plate disposed over the flyweights, skirt portions provided by the plate engageable by the weights at one extreme of their movement, thus limiting the outward travel of the flyweights, and means defining the angular relation of the skirt portion with respect to the flyweights, said defining means being alterable so as to vary the extent of outward travel of the flyweights.

13. In centrifugal means for an ignition timer, the combination comprising, a weight plate, flyweights carried by the weight plate, and a holdown plate secured in spaced relation to the weight plate for confining the movement of the flyweights, said holdown plate having skirt portions to be engaged by the flyweights at one extreme of their movement, and means for shifting the holdown plate relative to the weight plate for altering the extent of travel of the flyweights.

JAMES L. ARTHUR.
